UNITED STATES PATENT OFFICE.

EDWARD DENEGRE, OF CHICAGO, ILLINOIS, ASSIGNOR TO McCORD & COMPANY, OF CHICAGO, ILLINOIS, A CORPORATION OF NEW JERSEY.

CAR-AXLE BOX.

SPECIFICATION forming part of Letters Patent No. 770,681, dated September 20, 1904.

Application filed July 12, 1902. Serial No. 115,277. (No model.)

To all whom it may concern:

Be it known that I, EDWARD DENEGRE, a citizen of the United States, residing at Chicago, in the county of Cook and State of Illinois, have invented a certain new and useful Improvement in Car-Axle Boxes, (Case No. 3,) of which the following is a full, clear, concise, and exact description, reference being had to the accompanying drawings, forming 10 a part of this specification.

My invention relates to car-axle boxes, and has for its object the provision of an improved dust-guard therefor and also of improved means for holding the dust-guard in place.

Generally speaking, my invention relates 15 to that form of dust-guards known as "outside" dust-guards—that is, such that may be readily applied to axle-boxes, which boxes need not be structurally modified upon their 20 interiors in order to permit of the application of the dust-guards.

Generally speaking, my invention comprises 25 in one of its embodiments a dust-guard of this character formed in separable sections, whereby it may be readily placed about the car-axle and caused to close the opening in the car-axle box into which the car-axle projects. In practicing this feature of my invention I preferably form the dust-guard in two 30 equal sections that meet on a line coincident with a diameter of the axle, so that each half may be readily removed from a space about the axle, and in order to prevent any displacement between the sections when assembled they are provided with interlocking 35 means serving to maintain the same together, which interlocking means are preferably in the form of ears and lugs engaging recessed ears, one lug, with its engaging ear, being preferably diametrically opposite the other lug 40 with its engaging ear, the two ears being desirably provided upon one section of the dust-guard, while the two lugs are desirably provided upon a companion section. The interlocking lugs and ears are carried upon extensions of the dust-guard sections, which extensions are held in place by means of strip- 45 metal springs that pass through lugs carried

by the car-axle box and secure the said extensions close to the car-axle box to form a close fit therewith. The bore of the composite dust-guard is faced with some suitable material having direct contact with the car-axle, serving to permit the car-axle to rotate within the bore of the dust-guard without material friction, while at the same time preventing the admission of dust through the bore of the dust-guard.

I preferably employ as a packing for the dust-guards annular strips of suitable material 60 affording little friction and constituting a sufficient barrier to dust, which strips are preferably of leather. In order that these strips may be properly centered with respect to the bore of the dust-guard and axle, I provide an 65 annular rim which is concentric with the axle and the hole in the dust-guard, which annular rim surrounds the outer peripheries of the protecting-strips, while at the same time serving to properly center the same. In order to 70 prevent the packing-strips from buckling, rigid keeper-plates are mounted upon the outside thereof, rivets passing through the keeper-plates and the strips of packing material into the dust-guard body or plate, these keeper- 75 plates being substantially rigid, serving to confine the packing-strips to their normal planes between the rivets.

A dust-guard body or plate is made in sections. A plurality of annular strips of leather 80 is preferably employed, which strips are so laid as to break joints, by which construction not only may the plates of the dust-guard be separated, but the packing-rings as well, the keeper-plate permitting this separation, as in 85 such instance it is also made in sections, permitting separation between the dust-guard plate-sections.

I will explain my invention more fully by reference to the accompanying drawings, in 90 which—

Figure 1 is a side elevation of a car-axle box having associated therewith the device of my invention. Fig. 2 is a perspective view, of a preferred form of dust-guard constructed 95 in accordance with the invention. Fig. 3 is

an end view of the construction shown in Fig. 1 looking toward the dust-guard. Fig. 4 is a sectional view on line 4-4 of Fig. 3, the car-axle being shown in place, while one of the sections of the dust-guard is completely removed. Fig. 5 is a sectional view looking in the direction of the arrows 5-5 of Fig. 3. Fig. 6 is a sectional view on line 6-6 of Fig. 2.

Like parts are indicated by similar characters of reference throughout the different figures.

The car-axle box to which the device of my invention may be applied may be of any suitable character, that illustrated being a well-known type. This car-axle box is desirably provided with a marginal lug *a*, extending across its top and rear. The rear wall of the car-axle box is provided with a bore through which the car-axle *b* passes, this car-axle having interposed between the same and the top wall of the box a suitable bearing construction *c*, as is well understood by those skilled in the art. The dust-guard has two plate-sections *d*, each provided at its upper end with a hook *e*, that is engaged with the marginal lug *a*, as illustrated, the purpose of which lug and hooks will be more fully hereinafter set forth. The rear wall of the car-axle box is provided with lugs *f* at its top and bottom portions, through which horizontally-disposed strip-metal springs *g* are passed, whereby the sectional dust-guard plate is held against the rear wall of the car-axle box. In order that the dust-guard plate may be formed in separable sections, which at the same time when assembled may be retained in their proper relative positions, these sections are provided with some interlocking agency—as, for example, the lugs *h*, carried upon one plate, engaging correspondingly-recessed ears *i*, mounted upon the other plate. The lugs *h* by passing through the recesses in the ears *i* prevent relative vertical displacement between the sections of the dust-guard plate and also relative lateral displacement, the sections of the dust-guard plate forming practically a single dust-guard plate when assembled in the manner set forth. In the event of breakage of the upper spring *g* or of a buckling tendency between the plate-sections or any cause tending to effect an undue displacement of the dust-guard plate the hooks *e* come into service to act as a preventive against these undesirable consequences. The dust-guard plate is provided with a packing *k*, that projects within the aperture or bore through the plate and snugly surrounds the car-axle, and in order that the packing may be readily placed in position and may be always accessible for purposes of repair and replacement I mount the same directly upon the rear face of the dust-guard plate, and in order that the packing may always be centered properly there is employed an annular rim *l*, projecting rearwardly from the plate

and concentrically disposed with respect to the axle and with respect to the center of the bore through the dust-guard plate.

The packing *k* is preferably made up of annular strips of leather, which may be formed in sections and which may be riveted to the dust-guard plate at *l*' *l*'. In order to prevent the strips from buckling between the rivets, there is preferably employed a keeper-plate *m*, preferably made sufficiently rigid to properly retain the packing-strips. In the embodiment of the invention shown the dust-guard plate being formed in separable sections the packing-strips and the keeper-plates are also preferably formed in separable sections.

Having thus described my invention, I claim as new and desire to secure by Letters Patent—

1. A dust-guard for car-axle boxes, comprising a plurality of separable sections, and interlocking devices on said sections for temporarily locking the sections together, the different parts of said interlocking devices being fixed to said two separable sections, substantially as described. 85

2. A dust-guard for car-axle boxes, comprising a plurality of separable sections, and interlocking devices on said sections for temporarily locking the same together, the co-operating parts of said interlocking devices being 95 on the faces of said two separable sections. 90

3. A dust-guard for car-axle boxes, comprising a plurality of separable sections, and interlocking devices on adjacent edges of said sections for locking the same together, substantially as described. 100

4. A dust-guard for car-axle boxes, comprising a pair of separable sections separable along a line axial of the axle, and interlocking devices on opposite sides of the axle and 105 on the adjacent edges of the separable sections, said interlocking devices being adapted to engage one another to hold the sections of the guard temporarily against separation, substantially as described. 110

5. A dust-guard for car-axle boxes, comprising a plate formed in two sections, separable along a line substantially coincident with a diameter of the axle, the said plate-sections being provided with lugs *h*, *h*, and ears *i*, *i*, 115 whereby they are separably joined, substantially as described

6. The combination with a car-axle box, of a dust-guard comprising a plurality of separable sections, interlocking devices on said sections for locking the same temporarily together, and means for holding the guard in position on the box, said means being also arranged to hold the locking devices in a locked condition, substantially as described. 120

7. The combination with a car-axle box, of a dust-guard comprising a plurality of separable sections, locking devices on said sections for interlocking the same together, said devices consisting of sockets and projections 130

adapted to enter said sockets, strips or straps extended across the face of the guard for holding the same in position on the box, and means for holding said strips or straps in position also across said sockets, whereby the projections are held in position therein, substantially as described.

8. The combination with a car-axle box, of a dust-guard comprising a plate formed in composite sections, and strip-metal springs carried upon the rear of the car-axle box and serving to engage the dust-guard plate to hold the same close to the car-axle box, the sections of the said dust-guard plate being provided with interlocking means, and the strip-metal springs being arranged to hold said interlocking means in engagement, substantially as described.

9. The combination with a car-axle box, of a dust-guard comprising a plate formed in composite sections, and strip-metal springs

carried upon the rear of the car-axle box and serving to engage the dust-guard plate to hold the same close to the car-axle box, the sections of the said dust-guard plate carrying lugs 25 and ears, whereby they are separably united, substantially as described.

10. The combination with the plate of a dust-guard for car-axle boxes, of a rim projecting from the rear thereof, annular packing inclosed by the rim and centered thereby, and a keeper-plate inside of the rim fastened to the dust-guard plate, the packing being interposed between the keeper-plate and the dust-guard plate, substantially as described. 30 35

In witness whereof I hereunto subscribe my name this 26th day of June, A. D. 1902.

EDWARD DENEGRE.
